FLUE BUSHING

Stanley F. Jackes, St. Louis, and Reynold Gehne,
Pine Lawn, Mo., assignors to Jackes-Evans
Manufacturing Company, St. Louis, Mo., a cor-
poration of Missouri

Application June 20, 1938, Serial No. 214,704

6 Claims. (Cl. 126—318)

This invention relates to bushings, and with regard to certain more specific features, to flue bushings for stovepipes, and the like.

Among the several objects of the invention may be noted the provision of a bushing which is adapted more rigidly than heretofore to connect either end of a stovepipe section with a flue opening; the provision of a bushing of the class described which permits of said connection with 10 flues of various openings and of various wall thicknesses at their inlet openings; the provision of a bushing of the class described which is easy of application, and in the case of necessity, of easy removal; and the provision of apparatus of 15 this class which is simple to manufacture and which may be sold cheaply. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawing, in which is illustrated one of various possible embodiments of the invention,

Fig. 1 is a vertical section through a stovepipe and a flue, showing the application of the invention to a coal stove;

Fig. 2 is a view similar to Fig. 1 showing the application of the invention to a wood stove;

Fig. 3 is a vertical section on an enlarged scale, taken on line 3—3 of Fig. 1; and,

Fig. 4 is a vertical section showing a step in the application of the invention.

Similar reference characters indicate corresponding parts throughout the several views of the drawing.

The inlet openings 0 for flues, chimneys, and the like, heretofore have been made to fit the entering stovepipe quite loosely. This is not only because the masonry or the like, of which the chimney is made, is coarse, but also because the flue must be adapted to have connected therewith both so-called coal stoves (such as shown at 1 in Fig. 1) and also wood stoves (such as shown at 3 in Fig. 2).

Most stovepipe sections, such as shown at 5, are made with crimped, tapered ends 7, which are adapted to slide into and frictionally fit within uncrimped and non-tapered ends, such as shown at 9. This is in the case of both straight sections and elbows, as shown.

In the case of a coal stove its outlet 11 is made to fit within the receiving end 9 of a pipe section 5; whereas, in the case of the coal stove, such as shown at 3, the outlet 13 is made to receive therein the crimped and tapered end 7 of the pipe

section 5. The reason for this difference is that

in the case of a coal stove it is important that the relatively dense smoke be definitely projected into successive pipe sections, such as at 11 and 7; whereas, in the case of a wood stove, this consideration is not as important as the one that 5 the creosote or like condensate which collects in the pipe shall positively run back into the stove, and not run out at the joint, as it would if the pipe were set up as in Fig. 1.

From the above, it will be seen that, in the case 10 of a coal stove, the final pipe end that is to enter the flue opening 0 is relatively small; whereas, in the case of a wood stove, the relatively large pipe end enters the flue opening. It will thus be seen that, even with an accurately made 15 flue opening, it must be made large enough to receive the larger pipe end, which results in a loose fit for the smaller pipe end. Hence the pipes have been loosely connected in the flue openings in an unsafe manner in many instances. 20 A cementing operation to make a tight connection is expensive.

This invention also dispenses with unsightly wire braces and the like for anchoring the last pipe section at the flue opening.

We provide a bushing for use at the opening 0 which comprises a sleeve or thimble 17 (see Fig. 4), having an outwardly directed bead 19 around its central portion. Extending in one direction from the bead 19 is a crimped, inwardly tapered 30 end 21, corresponding to the tapered end 7 of a pipe section 5.

Directed from the opposite side from the bead 19 is a larger and relatively smooth, non-tapered end 23, corresponding to the ends 9 of a pipe 35 section 5. Both ends 21 and 23 of the thimble 17 fit into the flue opening 0, the relatively smaller end 21, of course, fitting with more clearance.

A separate flange 25 is provided, which is adapted to slip, either over the large end of the 40 thimble 17 or over its smaller end 21, but in either case abutting and fitting closely at one side or another of the outward bead 19, in order to effect a stop and peripheral closure and cover for the joint between pipe and flue. The flange 45 25 contacts the outer side of the flue or chimney, and is in turn contacted by said bead 19, also to prevent the thimble 17 from being pushed in too far.

In order that the thimble 17 may be prevented 50 from being pulled outward, the following construction is used:

On opposite sides of the bead 19 holes 27 and 29 are located for receiving a bolt 31. The bolt 31 has a square head 33 and is threaded to receive 55 a wing nut 35. The body of the bolt fits in either hole 27 or 29.

Inside of the thimble 17 is located a bar 37 of U-shaped section, as indicated in Fig. 3. The square or polygonal head 33 of the bolt 31 slid- 60

ably fits the U-shape of the bar. The bolt 31 also slidably passes through a slot 39 in the bar 37.

The end of the bar adjacent the bolt 31 is turned down at right angles to form a finger piece or handle 41. Its other end is hooked up as indicated at 43. To preserve its strength, the flanges of the bar, which determine its U-shape, are extended to the hook 43. At the end of the hook 43 is a claw or finger 45.

The thimble 17 is applied as follows:

Assuming that the crimped end 21 is to be applied to the flue opening 0, the bolt 31 is applied through the hole 27, as shown. The wing nut 35 is loosened so that the hook 43 and the finger 45 are positioned within the imaginary projection of the thimble cylinder (Fig. 4). Thus, the hook may readily pass into the flue opening 0 without the requirement of tilting the thimble or bushing 17. The wing nut 35 is then drawn up until the bar 37 is more or less parallel to the axis of the thimble 17. Before tightening the nut 35, the operator, while holding his thumb at A, pulls with his forefinger on the part 41, so that the claw 45 is drawn against the inside of the flue wall. The hook 43 thus holds the thimble 17 in place. The wing nut 35 is then further tightened to make permanent the tight connection. Since the polygonal head 33 of the bolt 31 has flats between flanges 37, it is not necessary to reach inside of the bushing 17 to hold the head 33 while turning the nut 35.

Should it be desired to reverse the thimble 17 in the flue opening 0, the flange 25 is applied from the end 23 of the bushing, thus becoming adjacent the other side of the bead 19. The wing nut 35 is then removed from the bolt 31 and the members 37 reversed in position, with the hook 43 extending from the end 23 of the bushing. This places the slot 39 adjacent the hole 29, so that the bolt 31 may again be positioned in the slot 39 and through the hole 29, the wing nut 35 being replaced.

After the thimble is in position, the pipe for connecting the stove thereto may be attached.

One of the advantages of the invention is that holding bars 37 may be carried in a collection separate from the collection of thimbles, and likewise the flanges 25 may be carried in a separate collection. Assembly may then be made according to the necessities of use.

Another advantage is that the operations for assembling the bushing in the flue opening 0 can all be made with great facility.

It is clear that, if desired, a plurality of the holding bars may be used around the periphery of the pipe.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawing shall be interpreted as illustrative and not in a limiting sense.

We claim:

1. A flue bushing comprising a centrally beaded thimble, an extension of one diameter extending from one side of said bead, an extension from the other side of a larger diameter, a flange adapted to be slipped over either of said exten-

sions and to abut said bead, said thimble having an opening in each extension, and a separately organized clamp bar adapted to be associated with either of said openings and to be moved into holding positions.

2. A flue bushing comprising a centrally beaded thimble, an extension of one diameter extending from one side of said bead, an extension from the other side of a larger diameter, a flange adapted to be slipped over either of said extensions and to abut said bead, said thimble having an opening in each extension, a separately organized clamp bar adapted to be associated with either of said openings and to be moved into holding positions, and manually operable clamping means for maintaining a predetermined position of the bar.

3. A flue bushing comprising a centrally beaded thimble, an extension of one outlet diameter extending from one side of said bead, an extension from the other side of a larger outlet diameter, a flange adapted to be slipped over either of said extensions and to abut said bead on either side thereof, openings on opposite sides of said beads, a draw bar having a slot adapted to be placed adjacent either opening, and manually operable clamping means adapted to pass through either opening and said slot.

4. A flue bushing comprising a centrally beaded thimble, an extension of one outlet diameter extending from one side of said bead, an extension from the other side of a larger outlet diameter, a flange adapted to be slipped over either of said extensions and to abut said bead on either side thereof, openings on opposite sides of said beads, a draw bar having a slot adapted to be placed adjacent either opening, manually operable clamping means adapted to pass through either opening and said slot, said draw bar being movable longitudinally of the axis of the bushing and having a hook at the end, the length of said draw bar being such that the hook protrudes from the end of the bushing.

5. A flue bushing comprising a length of pipe having a lateral opening therein, a draw bar having a slot adjacent said opening, said draw bar having a U-shaped cross section with the flat side adjacent the inside of the pipe, a hook at one end of the draw bar and beyond one end of the pipe, means at the other end of the draw bar for drawing the hook inwardly toward the pipe, a clamping bolt passing through the lateral opening and the slot and having a polygonal head fitting the groove formed by the U-shaped of the draw bar, and a wing nut on the outside of said bolt.

6. A flue bushing comprising a length of pipe having lateral holes therein, one each of which holes is closer to one end of the pipe than another, a hooked draw bar having slotted means adapted to be positioned adjacent one or the other of said holes when said hook is adjacent one or the other ends of the pipe, the draw bar being long enough to permit said hook to extend from the adjacent end of the pipe, and clamping means passing through the slot means and the adjacent holes permitting lateral swinging of said hook from its position within the projected cylinder of the pipe to a position outside of said projected cylinder.
